UNITED STATES PATENT OFFICE.

SAM CENTOFANTI, OF YOUNGSTOWN, OHIO.

FOUNTAIN PEN.

Application filed June 2, 1927. Serial No. 196,094.

This invention relates to a fountain pen, and contemplates a structure which is not only leak-proof, but one which will hold a minimum quantity of ink, and designed to be 5 quickly and easily filled as the occasion may require, the invention residing in the construction, the combination and arrangement of parts as claimed.

In the drawing forming part of this application, like numerals of reference indicate similar parts in the several views, and wherein:

Figure 1 is a view in elevation of the pen complete.

15 Figure 2 is a longitudinal sectional view taken through the pen.

Figure 3 is a sectional view on the line 3—3 of Figure 2.

20 Figure 4 is a sectional view of a modification.

Referring to the drawing in detail, 10 indicates the barrel of the pen which of course may be constructed from any suitable material and also vary in size without departing 25 from the inventive idea, the pen point or nib being indicated at 11. 12 indicates the removable cap which normally covers the nib 11 as illustrated in Figure 1, and adapted to be arranged upon the other end of the barrel 30 when the pen is being used as illustrated in Figure 2. As clearly illustrated in the drawing, the barrel 10 is provided with opposed longitudinal slots 13, which may be of any desired length depending upon the size of the 35 pen as a whole, these slots accommodating a transverse pin 14 arranged to slide in said slots, and provided with heads 15 as illustrated.

40 This pin 14 is associated with a hollow tubular plunger 16 arranged to slide within the barrel 10, and slightly spaced therefrom for the major portion of its length to facilitate movement of the plunger as the occasion may require. It will be noted that the lower end 45 of the plunger is slightly reduced and is surrounded by a ring of any suitable packing material indicated at 17 to prevent the ink from leaking through the slots 13 when the parts are arranged as shown in Figure 2.

50 The plunger 16 being hollow is also adapted to receive the quantity of ink together with the barrel 10, and in this way, a pen of any particular size can hold a maximum quantity of ink.

55 After the ink has been consumed, and if de-

sired to refill the pen, it is only necessary to arrange the plunger 16 in the lower end of the barrel, and after inserting the pen in the ink bottle or other suitable source of supply, the plunger is moved in the direction of the 60 other end of the barrel, thereby drawing a quantity of ink into the latter and also into the plunger 16. As shown in Figure 2, the plunger 16 is of a sufficient length to extend beneath the lower ends of the slots 13 when it 65 is in its uppermost position, which fact together with the packing ring 17 prevents leakage of the pen. The construction is very simple and easy to manipulate, the plunger being operated by simply taking hold of the heads 70 15 of the transverse pin 14, and moving the latter longitudinally of the slots 13.

The cap 12 which ordinarily covers the nib 11, is provided with a clip 18 which is designed to retain the pen within the pocket, as 75 will be readily understood. The inner end of the clip 18 extends through an opening provided in the cap and the extremity is bent flat against the inner wall of the cap, so that the end of the clip is substantially U-shaped, 80 as indicated at 19 in Figure 2 of the drawings. In order to securely retain the clip in place there is provided a holding member 20. This member is of hollow cylindrical formation and is closed at one end, its outer 85 diameter being such as to provide a snug fit within the cap. The member 20 is provided with a groove 21 to receive the inner extremity of the clip 18. An auxiliary cap 22 fits over the end of the cap 12 and carries a threaded stud 23. This stud passes through an opening provided in the cap 12 90 and has threaded engagement with the end of the holding member 20, so that the latter will securely hold the clip in place. 95

If desired, the clip 18 may be dispensed with and a screw eye 24 may be substituted for the threaded stud 23. This screw eye passes through the auxiliary cap 22 and the cap 12 and threaded engagement with the holding 100 member 20, as shown in Figure 4. This provides means for attaching the cap to a chain or ribbon.

105 While it is believed that from the foregoing description, the nature and advantages of the invention will be readily understood, I desire to have it known that I do not limit myself to what is herein shown and described, as such changes may be resorted to when desired as fall within the scope of what is claimed. 110

What I claim is:—

In a fountain pen, a barrel having opposed longitudinal slots, a hollow plunger slideable within the barrel and having a fluid-tight connection at its lower end with the interior of the barrel, and a transverse pin carried by the plunger and operating in said slots; and

utilized to move the plunger toward either end of the barrel, heads on both ends of said pin, and the edges of said slots being beveled, whereby said heads lie wholly within the diameter of the barrel.

In testimony whereof I affix my signature.

SAM CENTOFANTI.
